525/4****ABSTRACT**

The flammability of acrylonitrile-butadiene-styrene resin is significantly decreased by adding thereto a combination of a brominated aromatic ether and iron or chromium naphthenate.

The brominated aromatic ethers which may be used are illustrated by the generalized structure:

in which x is 2 to 5 and y is 0 to 5, provided x plus y equals at least 2. Examples of these compounds include decabromodiphenyl oxide, octabromodiphenyl oxide, hexabromodiphenyl oxide, pentabromodiphenyl oxide or tetrabromodiphenyl oxide.

The ABS resins which can be treated include the terpolymer produced by polymerization of acrylonitrile, butadiene and styrene monomers, as well as terpolymers produced by grafting acrylonitrile and styrene on polybutadiene, or blends of the component polymers.
